UNITED STATES PATENT OFFICE.

JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

MULTIPLE-COPYING MACHINE.

1,197,617.

Specification of Letters Patent. Patented Sept. 12, 1916.

Application filed November 8, 1915. Serial No. 60,251.

To all whom it may concern:

Be it known that I, JOHN J. FLANIGAN, a citizen of the United States, residing at Chicago, in the county of Cook and State 5 of Illinois, have invented certain new and useful Improvements in Multiple-Copying Machines, of which the following is a specification.

This invention relates to the art of multiple copying machines of the hectograph type, and has reference more particularly to that class of such machines employing a flat printing bed supported on a suitable frame, a duplicating band or apron 10 stretched thereover between receiving and delivery spools, and a removable impression device including a platen roll that is normally rolled over the bed in order to impress both the master sheet and the copy sheets 15 on the portion of the gelatin apron or band 20 that is supported by the bed.

The primary and general object of the invention is to produce a machine of this type that shall be of simple and durable construction, economical to manufacture, easy 25 to manipulate, not liable to get out of order, and shall be capable of neat, accurate and reliable work.

More specific objects are, to provide a 30 means for initially positioning and squaring the removable impression device relatively to the bed at the head end of the machine, to provide an improved means for squaring the paper sheet relatively to the 35 bed preliminary to rolling the same out over the latter, to provide an improved automatic lock for the platen roll of the impression device which shall hold the roll upon the bed during the rolling operation 40 and shall be automatically released for the insertion of the paper sheet when the impression device is in starting position, to provide, in association with a transverse gage bar, an improved means for gripping 45 the upper end portion of a sheet in the impression device and forcing the same down onto the bed without disturbing the correct registration of the end of the sheet with the gage bar, to provide an improved manner 50 and means of supporting the bed plate removably on the frame structure of the machine, to provide a convenient storage receptacle for containing and preserving the gelatin apron and its carrying spools when 55 not in use, as in storage or shipment, to pro-

vide an improved bearing for the spools of the apron, and to provide an improved automatic gravity lock or detent for said spools.

Other minor objects and advantages of the 60 invention will be apparent to those skilled in the art from the following description taken in connection with the accompanying drawings forming a part of this specification, in which—

Figure 1 is a top plan view showing the platen carriage in starting position at the head end of the machine and a sheet of paper introduced therein; Fig. 2 is a side elevation of the machine as viewed from the 70 left of Fig. 1; Fig. 3 is a longitudinal section taken on the line 3—3 of Fig. 1; Fig. 4 is a detail vertical section through the head end of the bed and the platen carriage, showing the latter part-way advanced over 75 the bed in the operation of rolling out a paper sheet thereon; Fig. 5 is a sectional detail on the line 5—5 of Fig. 1; Fig. 6 is a sectional detail at right angles to that of Fig. 5 on the line 6—6 of Fig. 5; Fig. 7 is 80 a detail view partly in elevation and partly in vertical section on the line 7—7 of Fig. 1, showing one of the spool bearings on one side of the machine; Fig. 8 is a detail view 85 in longitudinal section through the winding chuck of the receiving spool; and Fig. 9 is an elevation of one of the duplicate spools on which the copying apron or band is wound.

Referring to the drawings and describ- 90 ing first the stationary frame structure, 10 designates each of a pair of parallel vertical side plates that are rigidly connected and spaced at their lower portions by cross bars 11 (Fig. 3), the ends of which are turned 95 down to form legs 12 and are secured to the side plates by bolts or rivets 13.

14 designates each of a pair of distance rods that rigidly connect and space the upper portions of the side plates 10 above the 100 cross bars 11, and form supports for a removable bed plate 15. This latter, as is best shown in Fig. 3, has attached to its opposite sides near its front and rear ends front and rear angle brackets 16 and 17 respectively. 105 The depending portions of the brackets 16 are vertically slotted or forked as shown at 18 to straddle and rest upon the forward distance rod 14, and the rear brackets 17 are horizontally slotted or forked as shown at 110

19 to similarly engage the rear distance rod 14 under a horizontal sliding movement. To remove the bed plate its forward end is raised until the brackets 16 clear the forward distance rod 14, and then by a slight forward movement the rear brackets 17 are drawn clear of the rear distance rod 14. The bed plate is put in place by the converse of these operations performed in the inverse order in a manner readily understood. The bed plate is preferably furnished with a cloth covering 20 stretched thereover and suitably secured thereto, and the described removability of the bed plate 16 is mainly for securing greater compactness and convenience in shipping and storing and also greater convenience in cleaning the machine when necessary. The described mounting of the bed plate also enables it to be tilted up on its rear hinges to afford access to an underlying storage receptacle, hereinafter described.

Over the bed plate is stretched the usual gelatin duplicating apron or band 21, the end portions of which are wound on a pair of duplicate spools 22, one of which is located at the head end of the machine and constitutes the receiving spool while the other is located at the tail end of the machine and constitutes the delivery spool. When the band has been exhausted from the delivery spool and wound up on the receiving spool, the two spools are removed and interchanged and the band is then rewound 35 in the same direction, or the spools may be left in place and the band rewound in the reverse direction. By reference to Fig. 9 it will be observed that the heads of each spool have formed thereon or otherwise rigid therewith a longitudinally projecting squared portion 22^a and projecting longitudinally of the latter a cylindrical bearing spindle 22^b that is coaxial with the body of the spools, the two ends of the spool being 40 duplicates. At the head end of the machine one end of the spool thus formed is entered into a winding chuck 23 (Fig. 8) that is journaled in one of the frame plates 10 and is provided with a crank arm 24. The inner end of the chuck has a transverse slot 25 that receives the squared portion 22^a of the spool, and inwardly thereof a socket 26 that receives the cylindrical bearing spindle 22^b. Fast on the chuck is a ratchet disk 50 27 that is normally engaged by a gravity detent 28, Fig. 3, this latter being pivoted to the inner face of the side frame 10 on a pivot pin 29 and having an upward extension 30 that, when on one side of a vertical line 55 holds the detent engaged with the ratchet, and when swung to the opposite side of the vertical line maintains the detent out of engagement with the ratchet. The last described structure for supporting one end of 60 the spool is duplicated at the tail end of the

machine, with the exception that a turning knob 31, Figs. 1 and 2, is substituted for the crank 24.

The opposite ends of the spools are journaled in duplicate but reversely positioned bearings, one of which—that at the tail end of the machine—is illustrated in detail in Figs. 1 and 7, and consists of a U-shaped bracket 32 secured to the inner side of one of the side plates 10 and formed in its intermediate portion with a bearing 33 for the cylindrical bearing spindle 22^b of the spool, the latter being introduced to the bearing through a continuous downwardly, horizontally and upwardly extending slot or entrance way, designated as an entirety by 34. The spindle is maintained in the bearing by an underlying spring 35 which may readily be depressed to permit the passage of the spindle through the slot 34 when the same is 85 being introduced or withdrawn.

At the upper or head end of the bed-plate are mounted a pair of upstanding brackets 36 consisting of thin flat metal plates that are conveniently attached to the bed plate by inwardly bent lateral extensions 36', these latter conveniently lying between the under surface of the bed-plate and the bed-plate-supporting brackets 16 and conveniently secured by the same screw bolts or rivets 37 that secure the brackets 16 in place (Fig. 3). On and between these brackets 36 is pivotally mounted a gage bar 38 of angle form, Fig. 4, that is carried on a pair of arms 39 that are pivoted at 40 to the inner faces of the brackets 36. The gage bar 38 is normally supported directly opposite and flush with the head end of the bed 15 by pins 41 in the inner faces of the brackets 36 on which the free ends of the arms 39 rest. When the gage bar is swung upwardly and outwardly to the position indicated in dotted lines in Fig. 4 in order to permit the introduction of the receiving spool to its bearings, the arms 39 come to rest against similar stop pins 42.

The bracket members 36, aside from forming a support or carrier for the gage bar, also have an important function as a means for accurately supporting, positioning and squaring the platen carriage in accurate position for the introduction of a sheet of paper that is to be rolled out by the platen carriage over the bed. For this purpose the upper edges of the brackets 36 are each formed with notches 43 and 44, as most clearly shown in Figs. 2 and 4, which notches intimately coöperate with devices on the platen carriage in the manner hereinafter particularly described.

Considering now the impression device by which the paper sheets are impressed on the flat surface of the printing apron or band, I desire to note at the outset that this device is entirely unconnected to and re-

movable from the frame and bed of the machine, in contradistinction to machines of that type wherein the impression device is guidingly connected to the main frame carrying the printing bed, as typically illustrated in my former patents, No. 1,019,312, dated March 5, 1912; No. 1,118,119, dated November 24, 1914, and No. 1,141,702, dated June 1, 1915. Multiple copying or hectograph machines of a type which employ a wholly unconnected and removable impression device have hitherto been known, but, as commercially developed such machines have proved crude and unsatisfactory in operation and results owing mainly to the lack of any provision therein for securing anything like accurate positioning and alinement of the paper sheets on the printing bed. A lack of such provision means that where the printed lines on one sheet may be straight across the page, on the next sheet they may slant in one direction, on the next sheet they may slant in the opposite direction, and anything like uniformity of printing on a large number of copy sheets struck off from a single master sheet impression is an impossibility. An important object sought and attained in the machine of my present invention, therefore, is the production of a simple and comparatively inexpensive copying machine employing an independent or unconnected impression device which will nevertheless yield practically as good results in the matter of accuracy and uniformity of work as the more expensive and complicated machines employing an impression device which is positively guided throughout its entire travel over the printing bed. The frame of the impression device of the present machine consists of a pair of side plates 45 rigidly connected and spaced by a transverse bar 46, preferably integral therewith. On the transverse bar 46 is secured a pan or chute 47 that serves to guide the advance portion of the paper sheet into the impression device and between the rolls thereof, as hereinafter described. Pivottally suspended from the inner sides of the side plates 45 of the carriage frame are a pair of hanger arms 48 in and between the lower ends of which is journaled a steel gripping roll 49. The arms 48 are normally pressed forwardly by leaf springs 50 into engagement with stop pins 51. Pivottally mounted between the outer portions of the side plates 45, on pivots 52 is a bail-shaped yoke, in and between the parallel arms 53 of which is journaled a platen roll 54 that is preferably provided with a friction surface of rubber or like material. Secured centrally to the transverse member 55 of this yoke is an operating handle 56. When a sheet of paper, such as that indicated at 57, is to be entered into the impression device, the latter is at rest on the guide

brackets 36 of the main frame and the handle 56 is depressed, thereby swinging the platen roll 54 upwardly out of contact with the coöperating gripping roll 49 and permitting the forward end of the sheet to 70 be passed between said rolls. When this has been done, the handle 56 is raised carrying the platen roll 54 downwardly, pressing the gripping roll 49 backwardly against the springs 50 and carrying the upper portion 75 of the sheet down onto the bed, the extreme edge of the sheet having previously been positioned squarely against the gage bar. If the platen roll turned freely in its bearings, its described action in carrying the end of 80 the sheet down onto the printing bed would, through its rolling effect on the gripping roll 49, involve more or less displacement of the end of the sheet from the gage bar, since the tendency would be to draw the end of 85 the sheet away from the gage bar and thus distract or destroy the accurate alinement of the sheet secured by the gage bar. This is prevented by the application of a brake or drag to the platen roll which prevents it 90 from turning on its own axis until the paper has been brought into contact thereby with the printing bed. For this purpose I preferably employ the simple device shown in detail in Figs. 5 and 6 and comprising a 95 flat spring 58 that is secured at one end by screws or rivets 59 to one of the arms 53 of the yoke and at its other end is apertured for the passage of the spindle 54' of the platen roll 54 and presses a fiber or similar 100 washer 60 against a reduced end portion 54a of the roll, thus creating a frictional drag on the latter sufficient for the purpose described.

Secured to and projecting outwardly of 105 the outer sides of the frame plates 45 of the carriage are a pair of studs 61 and 62. When the carriage is accurately positioned upon the guide brackets 36 of the main frame the studs 61 lie in the notches 43 and 110 the studs 62 lie in the notches 44 of said brackets, so that the platen carriage as a whole is bodily supported and accurately positioned exactly transverse to the longitudinal axis of the main frame by the engagement of said studs with the notches of the brackets. While both sets of studs and their coöperating notches coöperate to this result, the studs 62 and notches 44 have an additional function to restrain the carriage from 115 riding or sliding down off the brackets until after the paper sheet has been introduced to the nip of the rolls and carried down onto the head end of the bed. When this has been done a further lifting movement 120 on the handle raises the studs 62 out of the notches 44 and permits the platen carriage to be then pushed forwardly over the printing bed, rolling out the sheet on the latter 125 as it progresses.

It is desirable to lock the platen roll in its lowered or working position before starting and during the traveling movement of the carriage and to automatically release it when the carriage has been returned to initial or paper-receiving position. It is also desirable to limit the swinging movements of the yoke which carries the platen roll. These results are obtained by the following described mechanism. The upper edges of the frame plates 45 are cut away in the form of notches 63, the ends of which form stops that coöperate with laterally projecting lugs 64 on the upper ends of a pair of uprights 65 that are mounted on the inner sides of the yoke arms 53, said lugs 64 striking the upper ends of the notches 63 when the handle is in its lowermost position and striking the lower ends of said notches when the handle is in its most elevated position. To effect the automatic locking of the yoke when the handle is raised and the platen roll is in working position, I pivot on the outer side of one of the frame plates 45 of the carriage (Fig. 2) an elbow lever 66, the upper arm 67 of which is formed as a latch member adapted to interlock with one of the lugs 64, while its lower arm 68 has a laterally projecting finger 69 that, when the carriage is mounted on the guide brackets 36 of the frame, rides on the upper edge of the adjacent bracket 36 and holds the latch arm 67 of the lever disengaged from the lug 64 against the action of a spring 70 tending to draw said latch arm down into locking engagement with the lug 64. As soon as the handle has been raised sufficiently to force the paper, by means of the platen roll, down onto the printing surface the spring 70 acts to swing the latch 67 down over the lug as shown in Fig. 4, and the yoke and platen roll are thereby locked in working position. A stop pin 71 below the arm 68 limits the downward swing of the locking lever when the impression device may be off the guide brackets with the handle in depressed position.

As machines of this character frequently stand idle for considerable periods of time it is desirable to preserve the duplicator band from dirt, the drying effects of the atmosphere and possible injury, in so far as possible, and for this purpose I have devised a simple and practical receptacle conveniently located in the machine frame for storing the band when not in use so that it comes out in practically the condition in which it was put away. This receptacle comprises a metal cylinder 72 (Fig. 3) having the general form of an elongated tin can with a tight fitting cap or cover, said receptacle being supported between the side frame plates of the machine by means of a pair of semi-circular straps or stirrups 73 secured to the latter. When the bed plate

is tilted up or removed the can 72 may be readily lifted from its supports, opened, and the duplicating band and its spools withdrawn and mounted on the machine. When the receptacle is closed, it obviously protects the contents from dirt, dust and possible injury; and, while not absolutely air tight it is practically so, holding the moisture and preventing the rapid drying out of the gelatin band.

In the operation of the device the removable platen frame or carriage is first placed at its initial or starting position supported on the guide brackets at the head end of the bed, and the handle is swung down, thereby separating the rolls and permitting the insertion of the advance edge of a paper sheet therebetween into abutting engagement with the gage bar, the sheet being squared by the latter and one side of the paper guide 47. The handle is then swung upwardly which causes the paper sheet to be gripped between the two rolls and its advance portion forced down onto the bed, during which operation any rotative movement of the platen roll is prevented by the brake device, thereby insuring the engagement of the paper with the gage bar during this operation and thus preventing any dislocation of the paper from proper position. The handle is then further elevated carrying the rearmost studs out of engagement with their seats in the guide brackets, whereupon the handle yoke is locked holding the platen roll in its lowered position and the platen carriage is then pushed forwardly, rolling the sheet out on and over the printing surface. The adhesion of the paper sheet to the gelatin printing surface and its engagement with the two rolls between which it is rolled out suffices to insure the straight forward movement of the carriage to the end of its travel in the absence of any abnormal sidewise movement imparted by the operator.

I claim:

1. In a multiple copying machine, the combination with a printing bed, of a removable impression device movable thereover, and means at one end of said bed co-operating with said impression device to support the latter in proper starting position elevated above the plane of the bed.

2. In a multiple copying machine, the combination with a printing bed, of a removable carriage carrying a platen roll adapted to be rolled over said bed, and means at one end of said bed co-operating with said carriage to support the latter in proper starting position elevated above the plane of the bed.

3. In a multiple copying machine, the combination with a printing bed, of a gage-bar opposite the head end of said bed, a removable carriage carrying gripping and

5 platen rolls adapted to travel over said bed, and means at the head end of said bed supporting said carriage in a starting position elevated above the plane of the bed and co-
operating with said carriage and gage-bar to accurately position a paper sheet on said bed.

10 4. In a multiple copying machine, the combination of a printing bed, a removable platen carriage adapted to travel over said bed, and guide brackets located at opposite sides of the head end of said bed serving to support and position said carriage elevated above the plane of the bed for the reception 15 of a paper sheet to be impressed on said bed.

20 5. In a multiple copying machine, the combination of a printing bed, a removable platen carriage adapted to travel over said bed and provided with a laterally projecting stud on each side thereof, and a pair of guide brackets located at opposite sides of the head end of said bed, each of said brackets having a seat adapted to be engaged by a stud on the adjacent side of said carriage to support the latter above and in starting position relatively to the bed.

25 30 6. In a multiple copying machine, the combination of a printing bed, a removable platen carriage adapted to travel over said bed and provided with a plurality of laterally projecting spaced studs on each side thereof, and a pair of guide brackets located at opposite sides of the head end of said bed, each of said brackets having a plurality of spaced seats adapted to be engaged by the studs on the adjacent side of said carriage to support the latter above and in starting position relatively to the bed.

35 40 45 50 7. In a multiple copying machine, the combination of a printing bed, a removable platen carriage adapted to travel over said bed and provided with a plurality of laterally projecting spaced studs on each side thereof, and a pair of upstanding guide brackets secured to and projecting above the head end of said bed on opposite sides of the latter respectively, each of said brackets being formed in its upper edge with a plurality of notches adapted to seat the studs on the adjacent side of the carriage and thereby support the latter above and in starting position relatively to the bed.

55 8. In a multiple copying machine, the combination with a printing bed, of a platen carriage having a gripping roll and a co-operating platen roll, the latter movable bodily toward and from said bed, means for separating said rolls to permit the insertion of a paper sheet between them, and means to prevent turning of said platen roll on its own axis while forcing the inserted end of said sheet down onto said bed.

60 65 9. In a multiple copying machine, the

combination with a printing bed, of a platen carriage having a gripping roll and a co-operating platen roll, the latter movable bodily toward and from said bed, a gage-bar opposite the head end of said bed, means for separating said rolls to permit the insertion of a paper sheet between them into abutting engagement with said gage-bar, and means to prevent turning of said platen roll on its own axis while forcing the inserted end of said sheet down onto said bed.

beneath said bed plate and having a closing cover independent of said bed plate.

16. In a multiple copying machine, the combination with a frame structure including 5 parallel side frame members, and a bed plate removably mounted on said frame structure, of supporting devices secured to the inner sides of said side frame members, and a normally closed storage receptacle for the 10 copying apron removably resting at its ends on said supporting devices beneath said bed plate.

17. In a multiple copying machine, the combination with a frame structure including parallel side plates, and a bed plate re- 15

movably mounted on said frame structure, of hangers secured to the inner sides of said side plates beneath said bed plate, and a normally closed cylinder for storing the copying apron removably supported at its ends on said hangers beneath said bed plate. 20

18. A multiple copying machine comprising a frame provided with ribbon spool bearings, one of said bearings consisting of a slot having an open ended vertical portion, a closed ended vertical portion and a horizontal portion joining said vertical portions, and a spring arranged to hold an end of a spool in the closed end of said slot. 25

JOHN J. FLANIGAN.
